UNITED STATES PATENT OFFICE.

FREDERICK E. POLLARD, OF NEW YORK, N. Y.

DESIGN FOR A WARDROBE.

SPECIFICATION forming part of Design No. 27,672, dated September 21, 1897.

Application filed June 25, 1897. Serial No. 642,349. Term of patent 7 years.

To all whom it may concern:

Be it known that I, FREDERICK E. POLLARD, a citizen of the United States, residing at New York, in the county of New York and State of New York, have invented a new and useful 5 Design for Wardrobes, of which the following is a specification.

The design is shown in the accompanying drawings, in which—

10 Figure 1 is a front view of a wardrobe embodying the design, and Fig. 2 is a sectional plan view thereof.

Referring to the drawings and in detail, the design comprises a wardrobe box or body portion B and a front casing or frame A, having uprights 14 and 15, a cornice 16, a horizontally-rolling partition or blind 13, and a vertically-

sliding blackboard 17. At the back are screen-work panels, uprights 10, and slats 11, having hooks 12, which break joints. 20

Wardrobes embodying this design are especially adapted for use in school-rooms.

Having thus fully described and illustrated the design, what is claimed is—

25 The design for wardrobes substantially as herein shown and described.

In testimony whereof I have hereunto set my hand in the presence of two subscribing witnesses.

FREDERICK E. POLLARD.

Witnesses:

J. H. WARREN,
D. R. RIXFORD.
